ARTHUR L. STANFORD, OF CHICAGO, ILLINOIS.

RAIL-ANCHOR.

1,267,602.

Specification of Letters Patent. Patented May 28, 1918.

Application filed October 8, 1917. Serial No. 195,325.

To all whom it may concern:

Be it known that I, ARTHUR L. STANFORD, a citizen of the United States, residing at Chicago, in the county of Cook and State of Illinois, have invented certain new and useful Improvements in Rail-Anchors, of which the following is a specification.

This invention relates to rail anchors of the general type shown in my Patent No. 1,196,488, issued to me August 29, 1916; and the object of the present invention is to provide means for maintaining the anchor in position on the rail flange, of such a character as will obviate the necessity for using threaded nuts or like threaded elements, which are somewhat expensive to provide and are otherwise objectionable.

The rail anchor of the present invention is one which may be fitted to place by the use of an ordinary hammer, sledge or the like, and a rail spike, and when in place will maintain itself rigidly under all conditions.

The rail anchor of the present invention is one which is fitted to turn or cant slightly on the rail flange when subjected to stress occasioned by the creeping tendency in a rail, so that practically all of the stress to which the anchor is subjected will be centered on one side of the rail, so that this gripping portion of the anchor must needs be made strong and rigid to withstand the strain put upon it.

The special features of the present invention pertain to the means provided for holding the gripping element in active relation to the rail flange, and since these holding means are not subjected to strain when in use they can be made relatively light without sacrificing strength or durability.

In the drawings illustrating the invention:

Figure 1 is a view showing the rail base in cross section, with the anchor of the present invention in gripping relation thereto;

Fig. 2 is an outer or back view of the rail anchor;

Fig. 3 is a top or plan view of the same with the rail removed;

Fig. 4 is a similar view showing the locking collar in position to be driven to place;

Fig. 5 is a perspective view of the locking collar;

Fig. 6 is a perspective view of a collar of slightly modified form; and

Fig. 7 is a top or plan view of a modification.

The anchor consists essentially of two parts, a rail gripping element 6 and a locking collar 7. The rail gripping element is substantially identical with that shown in Patent No. 1,146,488, and embodies a jaw 8 consisting of an overhanging portion 9 and a base portion 10 in spaced relation to one another. The jaw portion is reinforced at each end by outstanding flanges 11 and 11^a, the forward flange 11 at its lower end merging into a foot 12 slightly rounded on its forward or acting face 13, so that it will rock against the face of the adjacent tie, thereby causing the jaw to tilt or cant slightly when subjected to the action of a creeping rail, which rocking or canting of the anchor will be resisted at the lower end of the foot by the contact of the tie, so that a gripping or biting action will be exerted on the flange of the rail.

The foot is reinforced from behind by a web 14 which connects with and merges into the rearmost flange 11^a, and the jaw is further reinforced by a longitudinally extending rib 15 which bridges the space between the two flanges.

The metal composing the flanges 11 and 11^a is extended inwardly to afford converging connecting bars 16, 16, which, at the point of connection with the jaw element, are connected by a cross web 17. The connecting bars are of a length to extend under the rail base and to project for some distance beyond with their tips in contact, as shown in Fig. 4. The tips are in form to be engaged by a square locking collar 18, which is provided with a square aperture 19 having vertical and cross dimensions sufficient only to receive the two bars when in parallel relation to one another.

The locking collar is reinforced around its outer and inner faces by outer and inner flanges 20 and 21, the former of which on each side of the aperture is provided with rounded outwardly projecting lips 22 over which the tip ends of the connecting bars are adapted to be struck down and hooked over, as indicated in Fig. 3. The inner flange at its upper end is provided with a

jaw extension 23 adapted to be struck down to overlie the edge of the rail flange after the parts have been driven to place. In lieu of the jaw extension 23, a rigid or fixed jaw 24, like that shown in Fig. 6, may be provided, which, however, is adapted only to fit onto rails having definite flange dimensions, whereas the bendable jaw 23 may be fitted to flanges of any standard size.

In order to facilitate the striking down of the tip ends 25 of the connecting bars, the tips are inwardly rounded, so that when brought together as in Fig. 4 they will afford a recess or depression into which a spike or other pointed tool may be inserted for driving purposes.

In use, the gripping jaw will be driven into place on the flange of the rail and in close proximity to the face of the tie, and the collar will then be inserted, as indicated in Fig. 4, and afterward driven to place to abut against the opposing rail flange and the jaw extension struck down to engage the upper edge of the rail flange, as indicated. This driving in of the locking collar draws the converging connecting bars inwardly into parallelism within the collar, which can be readily accomplished by making the anchor of malleable iron; and in order to maintain the parts in locked relationship when the collar is driven to place, the tip ends of the bars are struck down and hooked over, as indicated in Fig. 3, by driving a wedge or spike between them and spreading them after the manner of a cotter pin. This method of locking the parts in place obviates the necessity for using screws or other threaded elements, which are relatively expensive to manufacture and are more difficult to maintain in locking relation.

Fig. 7 shows a slightly modified form of construction, in which a single connecting bar 26, provided with a split end 27, is employed in lieu of the companion connecting bars 16—16. In this modification, the locking collar is forced to place and the ends 27 are spread or struck over in the manner herein described. Although this modification of Fig. 7 does not possess the advantage of the wedging action which characterizes the preferred construction, nevertheless, this modified form may be successfully used in most cases.

The device as a whole is extremely simple and readily adaptable to rails of various sizes, and the gripping parts which are intended to resist creeping tendency are made strong and rigid, while the locking elements, which are simply designed to maintain the jaw elements in co-active relation with the rail, are made correspondingly light. The device as a whole is one which is extremely simple to manufacture and is easy of application, which are important features in the art to which the invention pertains.

In the preferred form of the invention, the two converging connecting bars constitute, in effect, a collapsible wedge, the ends of which will be forcibly drawn together by the driving on of the locking collar, so that the latter will tend, when driven to place, to fit tightly to the connecting means and will adapt itself to rail bases of varying width without the necessity for a machining or careful fitting of the parts, which is a matter of great importance in the manufacture of devices of this character.

From the description it will be noted that it is not the intention, however, to limit the claims to the preferred construction, since any construction in which the end of the connecting means may be spread, struck over or upset is within the scope of the invention, unless otherwise specified in the claims.

I claim:

1. A rail anchor consisting of a jaw member adapted to grip a rail flange, connecting means adapted to underlie the rail base, a locking member adapted to be driven onto the connecting means, and the connecting means having end portions adapted to be struck over to retain the locking member in position, substantially as described.

2. A rail anchor consisting of a jaw member adapted to grip a rail flange, connecting means adapted to underlie the rail base, a locking member adapted to be driven onto the connecting means, the connecting means having end portions adapted to be struck over to retain the locking member in position, and a jaw element on the locking member adapted to overlie the opposing rail flange, substantially as described.

3. A rail anchor consisting of a jaw member adapted to grip a rail flange and extended on its under side to furnish a foot adapted to abut against the tie, connecting means adapted to underlie the rail base, a locking member adapted to be driven onto the connecting means, and the connecting means having end portions adapted to be struck over to retain the locking member in position, substantially as described.

4. A rail anchor consisting of a jaw member adapted to grip a rail flange and extended on its under side to furnish a foot adapted to abut against the tie, connecting means adapted to underlie the rail base, a locking member adapted to be driven onto the connecting means, the connecting means having end portions adapted to be struck over to retain the locking member in position, and a jaw element on the locking member adapted to overlie the opposing rail flange, substantially as described.

5. In a rail anchor, the combination of a gripping member adapted to engage a rail flange, transverse connecting bars adapted to underlie the rail base, and a locking collar adapted to be driven onto the ends of

the connecting bars to abut against the opposite rail flange, and the ends of the connecting bars being adapted to be spread to hold the locking collar in locking relation to the 5 rail flange, substantially as described.

6. In a rail anchor, the combination of a gripping member adapted to engage a rail flange and provided with a depending foot adapted to abut against the face of the tie, 10 transverse connecting bars adapted to underlie the rail base, and a locking collar adapted to be driven onto the ends of the connecting bars to abut against the opposite rail flange, and the ends of the connecting bars being adapted to be spread to hold 15 the locking collar in locking relation to the rail flange, substantially as described.

7. In a rail anchor, the combination of a gripping member adapted to engage a rail flange, converging transverse connecting bars adapted to underlie the rail base, and a locking collar adapted to be driven onto the ends of the connecting bars to abut against the opposite rail flange, and the ends 25 of the connecting bars being adapted to be spread to hold the locking collar in locking relation to the rail flange, substantially as described.

8. In a rail anchor, the combination of 30 a gripping member adapted to engage a rail flange and provided with a depending foot adapted to abut against the face of the tie, converging transverse connecting bars adapted to underlie the rail base, and a locking collar adapted to be driven onto the ends 35 of the connecting bars to abut against the opposite rail flange, and the ends of the connecting bars being adapted to be spread to hold the locking collar in locking relation to the rail flange, substantially as described.

9. In a rail anchor, the combination of a gripping member adapted to engage a rail flange, transverse connecting bars adapted to underlie the rail base, a locking collar 45 adapted to be driven onto the ends of the connecting bars to abut against the opposite rail flange, and the ends of the connecting bars being adapted to be spread to hold the locking collar in locking relation to the rail flange, and a jaw member on the locking collar adapted to overlie the edge of the 50 opposing rail flange, substantially as described.

10. In a rail anchor, the combination of a gripping member adapted to engage a rail flange and provided with a depending foot adapted to abut against the face of the tie, transverse connecting bars adapted to underlie the rail base, a locking collar 55 adapted to be driven onto the ends of the connecting bars to abut against the opposite rail flange, and the ends of the connecting bars being adapted to be spread to hold the locking collar in locking relation to the rail flange, and a jaw member on the locking 60 collar adapted to overlie the edge of the 65

opposing rail flange, substantially as described.

11. In a rail anchor, the combination of a gripping member adapted to engage a rail flange, converging transverse connecting 70 bars adapted to underlie the rail base, a locking collar adapted to be driven onto the face of the connecting bars to abut against the opposite rail flange, and the ends of the connecting bars being adapted to be spread 75 to hold the locking collar in locking relation to the rail flange, and a jaw member on the locking collar adapted to overlie the edge of the opposing rail flange, substantially as described.

12. In a rail anchor, the combination of a gripping member adapted to engage a rail flange and provided with a depending foot adapted to abut against the face of the tie, converging transverse connecting bars 80 adapted to underlie the rail base, a locking collar adapted to be driven onto the ends of the connecting bars to abut against the opposite rail flange, and the ends of the connecting bars being adapted to be spread to 85 hold the locking collar in locking relation to the rail flange, and a jaw member on the locking collar adapted to overlie the edge of the opposing rail flange, substantially as described.

13. In a rail anchor, the combination of a gripping member consisting of a jaw having reinforcing flanges at its front and rear ends and adapted to engage a rail flange, a pair of connecting bars inwardly 100 extending from the front and rear flanges and converging toward one another, and a locking collar provided with an opening adapted to receive and engage the ends of the connecting bars, the bars being of a 105 length to project beyond the collar when driven to contact with the opposing rail flange and adapted to be hooked down over the collar to hold the same in place, substantially as described.

14. In a rail anchor, the combination of a gripping member consisting of a jaw having reinforcing flanges at its front and rear ends and adapted to engage a rail flange, a pair of connecting bars inwardly 110 extending from the front and rear flanges and converging toward one another, a locking collar provided with a slot adapted to receive and engage the ends of the connecting bars, the bars being of a length to project beyond the collar when driven to contact with the opposing rail flange and adapted to be hooked down over the collar to hold the same in place, and a jaw member on the collar adapted to engage the upper edge 115 of the opposing rail flange, substantially as described.

15. In a rail anchor, the combination of a gripping member consisting of a jaw having reinforcing flanges at its front and 120

- 4 rear ends and adapted to engage a rail flange, a pair of connecting bars inwardly extending from the front and rear flanges and converging toward one another, a locking collar provided with a slot adapted to receive and engage the ends of the connecting bars, the bars being of a length to project beyond the collar when driven to contact with the opposing rail flange and adapted to be hooked down over the collar to hold the same in place, and a depending foot on the rail gripping member having a rounded face and adapted to abut against the tie, substantially as described.
- 10 16. In a rail anchor, the combination of a gripping member consisting of a jaw having reinforcing flanges at its front and rear ends and adapted to engage a rail flange, a pair of connecting bars inwardly extending from the front and rear flanges and converging toward one another, a locking
- 15 17. In a rail anchor, the combination of a gripping member adapted to engage a rail flange, a connecting device in the form of a collapsible wedge and having a convergence away from the jaw member, and locking means adapted to be driven onto the converged end of the connecting means to draw in the same and furnish an abutment for the opposite rail flange, substantially as described.
